UNITED STATES PATENT OFFICE.

JAMES E. ANNEN AND GEORGE O. FROSTAD, OF MILWAUKEE, WISCONSIN, ASSIGNORS TO THE NATIONAL PAPER CAN COMPANY, OF MILWAUKEE, WISCONSIN, A CORPORATION OF WISCONSIN.

PAPER COVER FOR CONTAINERS.

Application filed March 21, 1922. Serial No. 545,531.

To all whom it may concern:

Be it known that we, JAMES E. ANNEN and GEORGE O. FROSTAD, citizens of the United States, each residing at Milwaukee, county of Milwaukee, State of Wisconsin, have invented a new and useful Improvement in Paper Covers for Containers, of which the following is a full, clear, and exact description.

10 The present invention relates to paper covers for containers such as paper cans. In the drawings the invention is illustrated as applied to a slip cover for a circular paper can.

15 Heretofore in making such covers, the paper at the edge has been bent at right angles to the cover top to form the flange. The paper has a certain amount of resiliency or "spring" so that there has been 20 a tendency for the flange to spring outwardly. As a consequence, slip covers have usually been made in two pieces, a separate piece of paper being employed for the flange. The object of the present invention 25 is to form the flange of the same piece of material as the body of the cover, thus saving expense, and at the same time to prevent the flaring out of the flange heretofore occurring in one piece covers. To prevent 30 this flaring or springing out of the flange, the paper at the base of the flange is bent or folded back so as to destroy the "spring" of the paper at that point.

The folded over base of the flange forms 35 a bead which strengthens and stiffens the cover and at the same time improves its appearance.

In the illustrated embodiment of the invention,

40 Figure 1 is a perspective view of a circular slip cover taken in vertical section through the middle of the cover, and

Figures 2 and 3 are detail sections showing modifications.

45 Referring to the illustrated embodiment of the invention and particularly to Figure 1, the cover which is illustrated as a slip cover is made of a paper disc. The edge portion of the disc is bent at substantially right angles to the disc body 1 to form the usual flange 2. The paper at the base of the flange is bent back upon itself at 3 to form a bead 4. It will be noticed from the drawing the

paper is bent back upon itself so that the bent back portion is substantially parallel 55 to the cover body. This sufficiently breaks the fibers to destroy the "spring" of the paper at this point and overcomes the tendency of the flange 2 to spring outwardly, which would otherwise occur. The bead 4 60 forms a thickened and stiffening ridge around the corner of the cover. In Figure 1 the center of the can cover is shown as depressed to form an ornamental bead or ridge 5 around the top of the cover. 65

In Figure 2 is illustrated a modification in which an auxiliary disc 6 is inserted inside of the cover. The edge of the disc 6 fits into the fold 3 where the paper is folded back upon itself. In Figure 2, the center of 70 the cover is shown depressed to provide the bead 5 around the top.

In Figure 3 is illustrated another modification in which an inner disc 6 is placed within the cover having its edge fitting in 75 the folded back portion of the cover. The auxiliary discs 6 may be used when it is desired to thicken and strengthen the top of the cover, or they may be omitted, as shown in Figure 1. 80

While the present invention has been specifically illustrated and described, it is to be understood that it is not limited to the illustrated embodiment, but may be otherwise embodied within the scope of the following claims. 85

We claim:

1. A paper container cover formed of a paper disc having its edge portion folded back upon itself and then bent substantially at right angles to the disc body, and an inner disc having its edge extending into the fold of the first disc, substantially as described. 90

2. A paper can cover formed of a paper disc having its edge portion first offset to form a ridge around the top of the cover, then folded back upon itself to form an outwardly extended folded bead, and then bent at right angles to the disc body to form a flange, substantially as described. 95

In testimony whereof we have hereunto set our hands.

JAMES E. ANNEN.
GEORGE O. FROSTAD.
